UNITED STATES PATENT OFFICE.

CHRISTIAN DANCEL AND JACOB RUPERT SCOTT, OF NEW YORK, N. Y.

MACHINE FOR FORMING BOOT OR SHOE COUNTERS.

SPECIFICATION forming part of Letters Patent No. 634,397, dated October 3, 1899.

Application filed September 13, 1898. Serial No. 690,880. (No model.)

To all whom it may concern:

Be it known that we, CHRISTIAN DANCEL, residing at New York, (Brooklyn,) county of Kings, and JACOB RUPERT SCOTT, residing at 5 New York, county of New York, State of New York, citizens of the United States, have invented new and useful Improvements in Machines for Forming Boot or Shoe Counters, of which the following is a specification.

10 This invention consists in certain novel features of construction set forth in the following specification and claims and illustrated in the annexed drawings, in which—

Figure 1 is a front elevation of the machine. 15 Fig. 2 is a side elevation of Fig. 1. Fig. 3 is a view like Fig. 2, showing the counter-carrier moved forward or away from the main body of the machine to receive a blank. Fig. 4 is a section along *t t*, Fig. 1. Fig. 5 is a section 20 along *u u*, Fig. 1. Fig. 6 is a section along *v v*, Fig. 5. Fig. 7 is a section along *w w*, Fig. 5. Fig. 8 is a section along *x x*, Fig. 1. Fig. 9 is a section along *y y*, Fig. 1. Fig. 10 shows a counter. Fig. 11 shows a blank for 25 a counter.

The frame or support of the machine is shown at 1 and the customary fast and loose pulleys at 2, Fig. 2, the fast pulley driving the worm-shaft 3, engaging the worm or gear 30 wheel 4, driving shaft 5. As seen in Fig. 9, this rotary shaft 5 does not extend clear through the machine, but only a part way across, and a second shaft 6 is fixed or non-rotatably secured to a suitable part or side of frame 1. A rotary bed 7 is connected or keyed to shaft 5, but sits loosely about the fixed shaft 6, so that it rotates with shaft 5. This 35 rotary bed 7 is provided with or carries a last 8, jaws 9, and wiper 10, and instead of having only one set of such parts it is found that 40 work is expedited by having a series of such parts on the bed. In the drawings these parts are shown in duplicate on opposite sides of the bed to be alternately or successively brought 45 into action. A description of the operation of one last, with its wiper and jaws, will of course explain the action of the others.

A counter-blank 11', Fig. 11, having been placed about the last or form 8 and pressed by 50 the jaws 9 and wiped by wiper 10 is brought into the counter shape shown at 11, Fig. 10, the wiper forming the lap or rand 12. The

blank 11' is delivered to the last 8 by a counter carrier or feeder 14, Fig. 3, the action of which will be presently described.

55

The jaws 9 swing on pivot 15, Fig. 7, and are compressed about the counter-blank or toward the last 8 by slides 16, which are actuated by cams 17, made to rotate or oscillate in suitable bearings in the rotary bed 7. These 60 cams have arms 18, and at the two sides of the frame 1 are suitably applied roller-studs 19 and 20, Figs. 1, 3, and 4. As the bed 7 rotates and carries the arms 18 against studs 19 the cams 17 are rotated or set to lock the slides 65 16 or to compress jaws 9 toward one another. The contact of arms 18 with studs 20 will move cam 17 to return or unlock the jaws 9. The slides 16 are shown in sections or two 70 parts with interposed elastic or yielding pads 21, Fig. 9, such as rubber, so as to avoid absolute rigidity, which might cause breakage. Rollers 22, Fig. 9, between slides 16 and jaws 9 will cause a rolling or easy motion of the parts. The jaws 9 could be opened by returning-springs 23, Figs. 1 and 7; but when each 75 cam 17 is made double-acting to positively lock and open the jaws the springs 23 can be omitted. The wiper 10 has two movements, one sliding to lap over the edge 12, Fig. 10, of 80 the counter and the other a pressure toward the center or shaft 6 to smooth said lap or rand 12.

The slide 25, Fig. 1, carrying wiper 10, moves along guides 24 on the rotary bed 7, 85 and said slide gives the lapping or wiping motion to the wiper 10. To the wiper-slide 25 at 28 is fulcrumed lever 26 27, the arm 27 giving the pressing movement to wiper 10. The slide 25 is engaged or actuated by lever- 90 arm 29, Fig. 5, whose fulcrum or shaft 30, Fig. 6, extends to opposite sides of the rotary bed 7 and has suitable bearings on such bed. At one end of shaft 30 is the arm 31, whose end or roller when bearing against cam 37, 95 Fig. 4, holds arm 29 raised or the wiper away from the last to allow a blank to be put in place. The cam 37 is suitably fixed to a side of frame 1, and as the rotary bed 7 rotates the arm 31 passes away from cam 37 and the 100 arm 34 of fulcrum 30 strikes roller 38, so as to cause the wiper to be slid or pushed over the edge of the blank projecting beyond last 8, so as to give the lap 12. As by the con-

tinued rotation of the bed 7 the arm 31 is brought back into contact with cam 37, such renewed contact will actuate lever 29 to withdraw the wiper for leaving the finished counter free to be removed. The pressure of the wiper is effected by arm 104, Fig. 6, suitably secured to end or part 32 of the hub or sleeve 39, seated about shaft 30 and having the toggle arms or connection 35 and 36, Fig. 8, reaching to arm 26 of lever 26 27. Secured or fixed to a side of the frame 1 are the roller-studs 40 and 41, Fig. 1. As the rotary bed moves arm 104 against stud 40 the toggle 36 is straightened out to press against lever-arm 26 and cause arm 27 to press wiper 10 toward the center point 6 or against the face of last 8. The bed 7 continuing to rotate and carrying arm 33 against stud 41 will cause the toggle to be bent for taking the lever 27 off the wiper 10, which latter is then moved by arm 31 and cam 37 away from last 8, so as to free the finished counter, which being removed from the last allows a fresh blank to be inserted. The arm 34 being made extensible or telescoping can be set so that the slide or wipe of the wiper is greater or less, as required. The arm 33 can also be adjustably secured to the head 32. A spring 42, Fig. 4, holds the arm 31 against cam 37.

30 The toggle is composed of the pieces 35 and 36, connected by the well-known elbow-joint, which allows piece 36 to swing in one direction until in line with piece 35 and then to stop or be held in such alignment until the 35 piece 36 swings back or flexes on piece 35 in like manner as the human forearm alines and flexes on the arm. Referring to Fig. 8, it is seen that the rotary bed turning in the direction of the arrow carries arm 104 against 40 roller 40, thereby swinging toggle arm 35 toward last 8. As the outer or free end of toggle branch 36 rests against lever-arm 26, this outer end is held or arrested against moving toward the last, and the swing of arm 35 toward such last will aline the parts 35 and 36, so as to cause them to be alined or extended to full length. The lever-arm 26 is thus pressed outward, causing arm 27 to press the wiper 10 inward or against the front or outer 45 face of last 8. By not causing the wiper to be pressed against the last until said wiper has slid or wiped over the last the sliding or wiping motion is easy or comparatively free from friction, and the subsequent pressure of the wiper toward the last or last-face causes the flange 12 to be neatly or firmly bent or set, so as to give the work satisfactory finish. The toggle branch 36 is not connected to lever 26, but simply abuts against the same, 50 this toggle 35 36, as seen in Fig. 6, being located at about the center of rotary bed 7, while the shaft 39 of arm 35 has the arm 104, located at one side to be in the path of the studs 40 and 41 on the frame 1. The arms 55 35 and 104 are rigidly connected to shaft 39, and arm 104 may have a roller, as seen in

Fig. 8, for relieving friction when this arm 104 glides past or strikes the studs 40 and 41.

The last 8 is slidable or movable toward and from the jaw joint or pivot 15, so as to shape or press the counter or blank firmly into the jaws. The lever 43 44, Fig. 5, is fulcrumed at 45 on the rotary bed 7, and its arm 43 has a set-screw 46, which can be made to bear against or hold the last 8 in proper adjustment. The lever-arm 44 has a roller or bearing-block 47 in contact with the cam 48, which, as seen in Fig. 9, is fixed or secured to the fixed shaft 6, so as to remain stationary, while the tubular or chambered bed 7, with the last 8 and fulcrum 45, rotates about such shaft 6. As the lever is carried about, its arm 44, contacting with the high part of cam 48, will move arm 43 to suitably slide or press last 8 into jaws 9, and at the point of intensest pressure the cam 48, Fig. 5, can be provided with a hardening 49, such as a piece of hardened steel, to resist friction or wear. An elastic or yielding pad 50, Fig. 5, such as rubber, between block 47 and lever 44 will prevent such absolute rigidity as might cause breakage. As seen in Fig. 5, the last 8 can be held to lever 43 or set-screw 46 by a spring 52. In order to relieve the pivot 15 from the pressure of jaw 8 and lever 43, the jaws 9, as seen in Fig. 5, are set into a recess or their upper or pivot portions bear against an overhanging portion 51 of the rotary bed 7. This seat 51, while not preventing the requisite degree of play or opening of the jaws, will save the pivot 15 from having to stand the strain or all the strain of lever 43, so that breakage or derangement of the pivot is avoided.

The counter carrier or feeder 14 when out in the position shown in Fig. 3 is in position to receive a blank 11', and by moving toward the machine, Figs. 2 and 5, such counter-carrier will deliver the blank onto the last. This blank-carrier 14 is adapted to slip or telescope into the sleeve 53, Fig. 5, and as said sleeve presses carrier 14 against last 8 and telescopes or slides over such carrier 14 such sleeve 53 slides the blank 11' off the carrier 14 onto last 8, where it is gripped by jaws 9, to be operated on or carried about by the rotary bed 7. The counter-carrier 14 has a stem 54, Fig. 5, extending or sliding through nut 55, and a spring coiled about stem 54 tends to move or hold the carrier 14 out of sleeve 53. By screwing the nut 55 more or less into sleeve 53 the carrier 14 is gaged or allowed to slip into sleeve 53 a less or greater distance, and the blank will thus be slid onto the last, so as to leave a greater or less projecting edge 125 portion to form a greater or smaller lap 12, as required. The sleeve 53 is carried by arm 56, which has a stud or movable connection 57 in the slot or guide 58 of plate or head 59. The plate 59 is mounted on arm 60, pivoted or 130 swinging at 61, Fig. 4, on the arm 62, depending from or connected to the frame 1 or to a cross-

bolt 63 of such frame. The way or guide 58 is cut or shaped so as to be centered or to lie circularly or concentrically about shaft 5, so that when the plate 59 has moved to the last 5 the arm 56, moving along the segmental way 58, will cause the carrier 14, with the blank, to follow the rotating bed 7 or its last 8 a certain distance until the jaws 9 have secured a hold on the blank. This motion of 10 arm 60 and the motion of arm 56 along way 58 are attained by cams or grooves on worm-wheel 4, Figs. 2, 3, and 9, the inner cam 64 being made to carry the head or support 59 toward and from last 8 and the outer cam 15 65 being made to move the connection 57 or arm 56 along way 58.

The frame 1 carries a fulcrum 66, Fig. 2, on which are shown two levers. The arm 67 of lever 67 68 on this fulcrum 66 is actuated or 20 engaged by cam 64, and the arm 69 of the other lever 69 70 is engaged by cam 65. The lever-arm 68 connects by link 71, Figs. 2 and 3, with arm 72 of bell-crank lever 72 73, having arm 73 connected by link 74, Figs. 3, 4, 25 and 5, with head 59. As the cam 64 moves from the position shown in Fig. 3 to that shown in Fig. 2 the lever-arm 68 is actuated to move levers 72 73 for swinging the arm 60, with head 59, arm 56, and counter-carrier 14, 30 to the last 8 or rotary bed 7. The lever-arm 70, Figs. 2 and 3, has link 76 connecting with arm 77 of lever 77 78, having arm 78 connected by link 79 with the lever or arm 80, fulcrumed at 63 and connected by link 81 with 35 the pin or traveler 57. As the cam 65 oscillates lever-arm 70 the parts 76, 77, 78, 79, 80, and 81 are moved to carry the arm 56 back and forth along guide 58. The fulcrums of the levers 72 73 and 77 78 are shown in the 40 form of suitably long shafts 82 and 83, Figs. 1 and 3, having the bearing 84, Fig. 5, carried or supported by the arm or riser 85, Fig. 4, on cross bar or bolt 63.

In placing the blank 11' onto the carrier 14 such blank can be properly gaged or centered by the fingers 86, Fig. 2, properly adjusted on cross-bar 87, carried by arms 88, extending from frame 1. A presser or finger 89 is arranged over the center of the carrier 14, Fig. 3, so as to press or hold the counter-blank onto such carrier. Such finger 89, as seen in Fig. 5, is surrounded or engaged by a spring arranged to press this finger onto the blank on the carrier 14; but of course this finger or 55 spring-piece 89 does not prevent the blank and carrier 14 from moving away from the position shown in Fig. 3 toward last 8. When the blank 11' is placed onto the carrier 14, such blank is bent by the operator about the 60 carrier and held so bent by fingers 90, Fig. 3, carried by slide 91 on stem 92, Fig. 5, said slide and fingers being temporarily held or pushed into position to keep the blank bent about carrier 14 until such bent blank is 65 pushed onto the last 8 and gripped by jaws 9.

The operation of the device is readily understood. A blank having been bent about

carrier 14, such carrier first moves to the last 8, and while the blank is being transferred from carrier 14 to the last the carrier traveling along way 58 follows or accompanies the last for some distance until the jaws 9 have gripped the blank. The last 8 being then pressed into the jaws and the jaws being pressed against the last or blank and the 70 wiper 10 being slid over and pressed against the overlapping or projecting blank portion, the counter is formed, as seen in Fig. 10. When finished, the counter is taken off the last by stripper 93, Figs. 2 and 3. Two strippers are shown for the double-acting machine, such strippers being mounted on arms 94, extending from shaft 95, to which are secured the arms 96. On the rotary bed 7 are arms 102 and 97, Fig. 4, which are applied to suitably engage and rotate the arms 96 with shaft 95 and stripper 93, which latter entering between the last 8 and the rand 12 of the counter on such last strips off such counter to leave the last clear for a fresh blank. The shaft 95 80 has its bearing on an arm 98, Fig. 4, suitably secured to the frame 1.

It has been stated that the cams 17, Fig. 9, can positively actuate the jaws 9 in both directions. By having links 99 connected to 95 the jaws and to the rear or return faces of the cams 17 such positive return or opening of the jaws can be secured. The jaws 9, Fig. 7, are separate or independent of one another and mounted on pivot 15, so as to swing laterally thereon or about such pivot. The last 8 and jaws 9 being made to act or press independently of one another, each can be made to act at the proper moment and with required force. After the jaws and last are fixed or 100 the last has been gripped by the jaws and the lever 44 has passed the boss 49 such lever 44 or cam 48 is somewhat relieved of pressure. The shaft 6, carrying cam 48, can be keyed fast to a frame side 1 or adjustably arranged, 105 as by screw and dog-piece, so that said cam and shaft, while non-rotary, can yet be accurately set or adjusted as required. The wiper-actuating lever or arm 34, Fig. 4, is shown provided with a stop-piece or nose 100, 110 which limits the play of said arm by striking against a stop-piece 101 on the rotary bed 7. The sleeve 39, Fig. 6, can be held by a brake or friction device 103 against improper movement or rotation. The last, wiper, and jaws 115 being so arranged that when under pressure or locked contact with the frame 1 or its studs and cams is avoided until the moment of unlocking, the rotary bed 7 will, between the period of locking and unlocking, move or rotate 120 freely or without any resistance from such frame studs and cams. The travel or rotation of the bed 7 can thus be effected economically or without waste of power. The cam or lock 17 for the jaws being so arranged 125 that when put in action or the jaws compressed said jaws are held locked and keep a hold on the last 8, the cam-actuating arm 18 can pass clear of the frame or the locking-

studs 19 without the jaws opening. The arm 18 clearing stud 19 relieves the rotary bed 7 of the friction or resistance arising from the contact of such parts 18 and 19, so that the bed can now rotate freely until arm 18 contacts with opening-stud 20. Also, when the wiper has been slid over the edge of the work or counter and the locking mechanism or toggle 35 36 has been locked or straightened by the contact of stud 40 said stud has been cleared or passed by arm 33, so that the rotary bed 7 travels or moves freely until arm 33 contacts with releasing or unlocking stud 41. Strain is thus relieved or unnecessary resistance to the movement of the bed avoided.

What we claim as new, and desire to secure by Letters Patent, is—

1. A last, a wiper and pivotally-mounted clamping-jaws, combined with mechanism substantially as described for actuating the wiper and jaws, arms 34 and 31 for respectively moving the wiper into and out of action, a roller 38 located in the path of the actuating-arm 34, a cam 37 for the releasing-arm 31, and a rotary bed 7 for carrying the arms to and from the roller and cam substantially as described.

2. A last, a wiper, a pivotally-mounted blank-carrier and jaws, combined with mechanism, substantially as described, for actuating the wiper, jaws and last, and for reciprocating the carrier to and from the last, substantially as described.

3. A last, a wiper, jaws and a blank-carrier having means for holding the blank bent thereon, combined with mechanism substantially as described for actuating the wiper, jaws and last and for reciprocating the carrier to and from the last substantially as described.

4. A last, a wiper, a blank-carrier and jaws, combined with mechanism substantially as described for actuating the wiper, jaws and last, a cam for moving the carrier to and from the last, and a cam for moving the carrier along with the last substantially as described.

5. A last, a wiper and jaws, combined with a blank-carrier, a support having a guide or way for the carrier, a cam-and-lever connection for actuating the support, and a cam-and-lever connection for moving the carrier along the guide substantially as described.

6. A last, a wiper, a pivot, and jaws on said pivot, combined with a lever 29 for sliding the wiper over the last, a toggle for pressing the wiper toward or against the last, and mechanism substantially as described for actuating the last and jaws, said jaws being made to swing laterally about said pivot, substantially as described.

7. A last, a wiper and jaws, combined with a rotary bed on which the last is mounted mechanism substantially as described for actuating the jaws and last mechanism for giving a sliding movement to the wiper and mech-

anism for giving pressure to the wiper substantially as described.

8. A last, jaws, a wiper, and a pressure-lever fulcrumed to the wiper, combined with actuating mechanism substantially as described for the last, jaws, wiper and lever said wiper being free to slide or wipe over the face of the last and to move or be pressed toward and from the face of the last. 75

9. A rotary bed, combined with a series of suitably-actuated lasts, wipers and jaws mounted on and carried by the bed, said bed being made to alternately or successively carry about the last, wipers and jaws substantially as described.

10. A last, a wiper and jaws combined with a rotary bed on which said last, wiper and jaws are mounted mechanism substantially as described for actuating the wiper and last, 85 and cams for positively closing and opening the jaws substantially as described.

11. A last, a wiper and jaws, combined with actuating-levers for the last and wiper, actuating slides and cams for the jaws, and returning-links 99 connected to the cams and jaws, substantially as described.

12. A last, a wiper and jaws movable on a common bed, combined with actuating-levers for the wiper, actuating-slides for the jaws, 95 and a fixed cam and actuating-lever for the last substantially as described.

13. A last, a wiper and jaws, combined with actuating-levers for the wiper, actuating-slides for the jaws, a cam and actuating-lever 100 for the last, a rotary bed for the last, wiper and jaws and a shaft on which said cam is fixed or immovably mounted and about which the bed rotates substantially as described.

14. A last, a wiper and jaws, combined with actuating or pressure mechanism substantially as described for said parts, said jaws and last being made to act or press independently of one another and said wiper being made to move toward and from the outer or front face of the last substantially as described.

15. A last, a wiper and jaws, combined with a blank-carrier, and a gage for centering or adjusting a blank on the carrier said gage 115 comprising a central spring-pressed finger 89 for holding the blank to the carrier, and laterally-adjustable fingers 86 for engaging the ends of the blank substantially as described.

16. A last, a wiper and jaws, combined with a blank-carrier, a cross-bar at said carrier, and a gage or fingers adjustable on the bar substantially as described.

17. A last, a wiper and jaws, combined with a blank-carrier, a cross-bar at the carrier, and a central spring piece or finger to hold the blank to the carrier substantially as described. 125

18. A last, a wiper and jaws, combined with a blank-carrier, and fingers or holders for keeping a blank bent about the carrier substantially as described.

19. A last, a wiper, and jaws, combined with a blank-carrier, fingers or holders for keeping a blank bent about the carrier, and a slide for moving the fingers into and out of action substantially as described. 5
20. A last, a wiper and jaws, combined with a blank-carrier, and a pivotally and slidably mounted support on which the carrier is mounted substantially as described. 10
21. A last, a wiper, and jaws, combined with a blank-carrier, a support on which the carrier is loosely mounted, and a gage for limiting or adjusting the yield or movement of the carrier on its support substantially as described. 15
22. A last, a wiper, and jaws, combined with a blank-carrier, a hollow or tubular support into which the carrier can slide or yield so as to leave a projecting blank portion to be engaged or lapped by the wiper substantially as described. 20
23. A last, wiper and jaws, combined with a carrier made to deliver a blank or counter to the last and to follow the motion of the latter until the counter is held by the jaws substantially as described. 25
24. A last, a wiper, and jaws, combined with a shaft about the center of which said parts rotate, and a carrier having a way or guide centered about the shaft to cause the carrier to follow the last substantially as described. 30
25. A shaft, and a last, wiper and jaws made to rotate with or about said shaft, combined with cams, levers actuated by said cams, and a blank-carrier, one of said levers being made to move the carrier to and from the last and the other lever being made to move the carrier about the shaft substantially as described. 35
26. A last, wiper and jaws, combined with a shaft for said parts, a driving-wheel for said shaft, cams on opposite faces of said wheel, levers actuated by said cams, a swinging support provided with a guide, a blank-carrier movable along the guide, and links or connections between the levers and the support and carrier substantially as described. 40
27. A frame or support and a bed provided with a last, wiper and jaws, combined with roller studs and cams fixed to the frame rotary cams and slides for actuating the jaws, a lever and a toggle for actuating the wiper, and a lever for actuating the last, said levers and toggle together with the rotary cam being actuated by the studs and cams on the frame, substantially as described. 45
28. A last and jaws and mechanism substantially as described for actuating the same, combined with a wiper, and a locking-stud for the wiper fixed to the frame and locking-cam for the wiper whereby said wiper is operated positively in both directions substantially as described. 50
29. A last and wiper and mechanism substantially as described for actuating the same, combined with jaws, rotary cams for actuating the jaws and locking and unlocking studs for the jaws said jaw-actuating cams having arms made to alternately strike and pass out of contact with the studs substantially as described. 55
30. A last, a wiper and jaws, combined with a pressure-lever for the wiper, a toggle connection for actuating the lever, and studs for moving the toggle into and out of action substantially as described. 60
31. A last, a wiper and jaws, combined with a pressure-lever for the wiper, a toggle connection for actuating the lever, an unlocking-arm for the toggle, and studs for the toggle and arm substantially as described. 65
32. A last, a wiper and jaws, combined with a stud and actuating-arm for sliding the wiper into action, said arm being adjustable to regulate the slide of the wiper substantially as described. 70
33. A last, wiper and jaws, combined with a pressure-lever for the last, a fixed cam for the lever, and a hardened face part or boss on the cam, said jaws being made to hold the last when the lever has passed the boss to relieve such lever of part of the pressure and said boss being in a separate piece from said cam substantially as described. 75
34. A rotary bed provided with a last, wiper, jaws and a fixed pivot for the jaws, said last being made to press or move into the jaws and said bed having a seat or recess to which the upper or pivot parts of the jaws are fitted to take up pressure of the last against such jaws, substantially as described. 80
35. A bed provided with a last, wiper and jaws, a lever for the last, a cam for the lever, a shaft for the bed made to support the cam, and a frame to which the shaft is fixed or connected substantially as described. 85
36. A frame provided with a rotary or actuating and a non-rotary shaft, a chambered bed keyed or fixed to the actuating-shaft and made to rotate about the fixed shaft, and a last, wiper and jaws on said bed substantially as described. 90
37. A bed provided with a last, wiper and jaws, an actuating-lever for the wiper, and a lateral arm on the lever adapted to engage a relatively fixed part for limiting the movement of said lever substantially as described. 95
38. A bed provided with a last, wiper and jaws, a lever having an adjustable arm for actuating the wiper, and a cam and stud for actuating the lever, said adjustable arm having a stop-piece substantially as described. 100
39. A frame, and a bed provided with a last, wiper and jaws and with locking mechanism substantially as described, said frame having studs and cams for locking and unlocking said mechanism and said locking mechanism being made to hold the last, wiper and jaws locked and to remain clear of or free from pressure or contact with the frame between the periods of locking and unlocking so as to allow the bed to move or rotate freely substantially as described. 105
40. A frame provided with a shaft and with

locking and unlocking studs and cams, a rotary bed on the shaft provided with a last, wiper and jaws and with locking mechanism substantially as described actuated by the 5 studs and cams and made to remain clear of or free from pressure or contact with the frame at suitable intervals to allow the bed to move or rotate freely substantially as described.

41. A bed provided with a last, wiper and 10 jaws and with locking mechanism substantially as described mounted on or carried by the bed so as to travel therewith for allowing the bed to move or rotate freely and automatic means for positively releasing said locking 15 mechanism substantially as described.

42. A frame, and a bed provided with a last,

wiper and jaws and with locking mechanism substantially as described, said locking mechanism being made to contact with the frame and to clear the latter after having been locked 20 and automatic means for positively releasing said locking mechanism substantially as described.

In testimony whereof we have hereunto set our hands in the presence of two subscribing 25 witnesses.

CHRISTIAN DANCEL.
JACOB RUPERT SCOTT.
